(57) **CLAIM**

The ornamental design for an automatic faucet, as shown and described.

DESCRIPTION

FIG. 1 is a perspective view of an automatic faucet showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures are included for the purpose of illustrating portions of the automatic faucet that form no part of the claimed design.

The dash-dot-dash broken lines in the figures represent unclaimed boundary between claimed and unclaimed subject matter.
